**COMBINED DIAL AND HANDS FOR A CLOCK OR
SIMILAR ARTICLE**

Thomas E. Benford and Lewis E. Clark, St. Louis, Mo.

Application August 4, 1955, Serial No. 37,312

Term of patent 7 years

(Cl. D42—1)

Fig. 1 is a front elevational view of a combined dial and hands for a clock or similar article, showing our new design;

Fig. 2 is an edge view of the combined dial and hands for a clock or similar article as shown in Fig. 1.

We claim:

The ornamental design for a combined dial and hands for a clock or similar article, as shown.
